CONVEYING SYSTEM

Allen L. Stone, San Francisco, Calif., assignor, by
mesne assignments, to Pneumastic Co., Inc., a
corporation of Nevada

Application December 20, 1937, Serial No. 180,789

4 Claims. (Cl. 198—43)

The present invention relates to improvements in conveying systems, and is concerned more particularly with the provision of an improved system of the character referred to which can be used for conveying building materials such as plaster or concrete and other materials of similar character in a simple and expeditious manner to a desired point or points of disposal.

It is a general object of the invention to provide an improved conveying system of the character referred to.

Another object of the invention is to provide an improved conveying system which does not require complete filling to deliver material, so that the exact amount of material can be conveyed which is desired for use.

Another object of the invention is to provide a distributing system which provides a continuous circulation of materials such as plaster or concrete, so that a supply is always available at any point along the system, and so that the material carried thereby is agitated constantly to avoid becoming unworkable.

Another object of the invention is to provide a conveying system which is self-cleaning and therefore avoids expensive conditioning work when its operation is stopped.

Other objects of the invention will appear from the following description of a preferred embodiment as illustrated in the accompanying drawings, in which

Fig. 1 is an elevational view of a hoisting and distributing system embodying the invention with a part of the structure including the tower shown somewhat diagrammatically.

Fig. 2 is a sectional view of a portion of the distributing conveyor showing the feed end of such conveyor and its connection to the hopper associated therewith, the plane of the view is indicated by the line 2—2 in Fig. 6.

Fig. 3 is a plan view, in section, of the base of the hoisting tower, the plane of the view being indicated by the line 3—3 in Fig. 4.

Fig. 4 is a vertical sectional view through the base of the hoisting tower taken in a plane indicated by the line 4—4 in Fig. 3.

Fig. 5 is a sectional view through the base of the hoisting tower taken in a plane of the line 5—5 in Fig. 4.

Fig. 6 is a plan view of the top unit of the hoisting tower.

Fig. 7 is a vertical sectional view through the top unit of the tower, being taken in the plane of the line 7—7 in Fig. 6.

Fig. 8 is a vertical sectional view of the top

unit, being taken in the plane of the line 8—8 in Fig. 7.

Referring to Fig. 1, the hoisting and distributing apparatus includes a hoisting unit or tower 5 comprising base 15, a plurality of intermediate tower sections 16 and a top section 17 with which is associated a horizontally disposed distributing unit or conveyor 18. On the tower base 15 there is provided an engine 19, a mixer 20 suitably driven therefrom, and a hopper 21 which receives material through a feed chute 22 from the mixer 20. Mounted on the tower is a hoisting and circulating system including ascending and descending tube conduits 23 and 24 communicating with the hopper 21, and through which an endless conveyor 25 is driven. Generally, the operation of the apparatus is to mix the plastic material such as plaster or the like in the mixer 20, which may be of conventional construction, 10 and from which it is delivered to the hopper 21 which comprises a part of the vertical hoisting and circulating system in which the material is kept in constant agitation, being conveyed up through conduit 23 and then either returned to the hoist hopper 21 through conduit 24 or deposited in a distributing hopper as described hereinafter.

Preferably, the tower base 15 includes a supporting frame or platform 26 provided with sets 30 of wheels 27 to enable movement of the tower from one location to another. The base section of the tower is carried by the frame 26 and may comprise vertically disposed angles of posts 28 at the four corners of the tower which are joined 35 by horizontally disposed angles 29 at the top and at the bottom. As seen most clearly in Figs. 4 and 5, the hopper 21 is provided with a V-shaped bottom 31 which terminates in a trough 32 of semi-circular cross section to receive the conveyor 25 and form a part of the circulating system. At the discharge side of the hopper 21 a surge chamber 33 is provided above trough 32 by formed hood 34 secured above the trough and by arcuate strip 36 closing the end of the trough. The surge chamber 33 leads upwardly to a vertically disposed tube 37 secured to a horizontal angle 29 by a U-bolt 38 and forming the lower part of the hoisting conduit 23. Above the opposite end of the trough 32 a similar tube 39 40 is mounted similarly to provide the lower section of the return conduit 24 of the hopper and the respective tubes 37 and 39 form the bottom portions of the elevating and return runs of the hoisting and circulating system.

Above the base section of the tower each suc-

cessive tower section may comprise similar post angles 28a and horizontal angles 29a together with diagonally disposed braces 41 suitably connected thereto. It will be noted that the upper and lower horizontal angles of each section 16 are apertured to receive fastening bolts 42 by means of which the tower sections may be built up from the base to provide a tower of any desired height. Each tower section also includes a pair of opposite tube sections 43 of the respective conduits 23 and 24, the tube sections being suitably mounted on the associated frame section by U-bolts 38.

To connect adjacent tube sections, the lower end of each section 43 (Figs. 5, 7, and 8) is provided with a collar 44 secured thereon, as by welding, and having a vertically disposed wedge 46 formed thereon opposite a vertical slot 47. Cooperating with the wedge 46 and the slot 47 is a clamp collar 48 which is also slotted and loosely disposed about the collar 44 to engage over the wedge 46. Thus when the adjacent end 43a of a pipe section is placed within the collar 44 in end to end cooperative relation with the tube 43, the clamp collar 48 can be driven downwardly over the wedge 46 to contract the slotted collar 44 into clamping engagement with the end 43a of the cooperating tube section, and then the collar 48 may be driven laterally to twist slightly about the inner collar 44 and become firmly wedged in place. Similarly, the connection can be released easily by driving the clamp collar 48 in the opposite direction. It will be noted that the type of coupling disclosed not only provides for simple connection and disconnection between adjacent tubes, but also effectively prevents any clogging or corrosion of the cooperating parts by the material being handled.

The top section of the tower 17 has a frame section including corner posts 28 and horizontal angles 29 similar to the other tower sections and is similarly mounted on the adjacent tower section 16. The conduit means of the top section includes a tube 91 leading from the adjacent tube 43 of the hoisting conduit 23, the tube 91 terminating at its upper end in a curved hood 92, and a tube 93 forming a part of the return conduit 24 and having a flared upper end 94 to receive the conveyor flights.

It will be understood that the intermediate sections 16 of the tower are interchangeable, and can be erected successively by being placed in position on the base, and then one on top of another, by installing the fastening bolts 42 and by tightening the clamp collars 48. The top section 17 of the tower is similarly erected on the uppermost intermediate tower section 16. Thus is it seen that the opposite vertically disposed conduits of sectional tubing provided form a part of a circulating system with the hoist hopper, and conveying means is associated therewith in the form of an endless cable 51, which is preferably also made up in sections to enable adjustment of its length to correspond to the height of the tower.

On the cable 51 a series of conveying flights are provided, each flight comprising a disc 52 of fibre or other suitable material held on the cable 51 in any suitable manner. The cable 51 is preferably also of sectional construction, the sections being connected by suitable joints, and it is preferred to make the cable section of a length to enable addition or removal of one or more sections thereof in adding or removing tower sections.

The conveyor flights on the cable also serve to receive the drive for the conveyor, and to cooperate therewith a pair of driving sprockets 61 (Fig. 4) are secured on respective transverse shafts 62 extending through the bottom wall 31 of the hopper 21 and journalled by bearings 63 on horizontal frame angles 64. One of shafts 62 is provided with large sprocket wheel 66 which is driven through chain 67 from the engine sprocket 68. Adjacent sprocket wheel 66 a smaller sprocket wheel 69 is provided which is connected by chain 71 with sprocket wheel 72 on the other shaft 62. As seen in Fig. 4, each drive sprocket 61 is provided with a plurality of sprocket arms 76, three in number being shown, which are flat on one face and are bifurcated at the end to provide a disc engaging socket 77 which is defined by curved wall formed to fit the adjacent flange 54 of the disc.

The sprockets 61 drive the cable in the direction of the arrows in Fig. 4 so that material deposited in hopper 21 and flowing downwardly into trough 32 will be carried into the surge chamber 33 which will be kept substantially full of the material which is agitated constantly and the sprocket arms 76 having a width to fit closely within the walls of hood 34. As the flights of the conveyor travel through the surge chamber, each flight will lift a charge of material as it travels upwardly into the tube 37. It will be noted that because of the flexible character of the cable, a flight thereof can yield as it passes into the tube 37 in the event a stone or other obstruction is caught between the flight and the tube. Usually the amount carried by a flight will occupy about half of the space between adjacent flights. As the material is carried upwardly it may be selectively delivered from any section of the tower by means of a hinged gate 81 in the tube section 43 thereof pivoted at 82 and having a control lever 83 which may be operated from any convenient location by a cord 84 to open the door against the tension of the spring 86. Then as a disc passes by part or all of the material may flow outwardly and be caught by suitable trough and conveyed by a flexible hose or the like to any desired point of disposal.

To support and guide the conveyor between tubes 91 and 93 a sprocket wheel 96 is provided on a shaft 97 journalled by bearings 98 on the uppermost angles 29, the sprocket 96 being driven by the conveyor flights for a purpose later described. At the opposite side of the tower top a second idler sprocket 99 is provided on a shaft 100 from which the conveyor extends downwardly into the return conduit 24.

Selective distributing means are provided at the top of the tower whereby the material which is carried upwardly, may be returned so as to circulate through the system or may be discharged if it is desired for use. For this purpose a discharge chute 106 is suitably mounted in the tower top 17 and is provided with an inclined portion 107 which is disposed to receive material discharged from the tube section 91 and which terminates in a discharge trough 108 having its discharge end 109 disposed over a distributing hopper 111 referred to hereinafter. Also leading from the discharge chute 106 is a conduit 112 (Figs. 1, 6 and 8) leading from the bottom of the chute to the tube section 93 of the return conduit. The top of the conduit 112 is normally closed by a gate 113 hinged at 114 and forming a part of the bottom wall of the chute 108. By lifting the gate 113 to the dotted line

position shown in Fig. 8, the material discharged from the tube section 91 will travel through the discharge chute into the conduit 112 and back to the tube section 93 for return to the hopper 21. With this adjustment of the parts, a drive of the hoisting conveyor will merely accomplish circulation of material through the hoisting system.

When the gate 113 is closed, the material will flow down the chute 108 and be discharged into the distributing hopper 111 which is pivotally mounted at 116 on a platform 117 suitably secured to the tower top 17. The bottom wall 121 of the distributing hopper 111 (Fig. 2) is inclined to lead to a surge chamber 122 secured thereon and housing a drive sprocket 123 similar in construction to those heretofore described and having its shaft 124 (Fig. 6) driven through universal joints 125 and telescoping shaft 126 from a sprocket 127 which is driven by chain 128 from a sprocket 129 (Fig. 1) on shaft 97. In this manner, a universal drive connection is provided to accommodate swinging movement of the distributing conveyor relative to the tower.

Associated with the sprocket 123 is the distributing conveyor 18 similar in construction to the elevating conveyor and supported from the tower by a cable 131. If desired, the conveyor 18 may be supported from suitable outriggers on the adjacent building wall. The conveyor 18 comprises a horizontally disposed circulating system made up of a series of opposite tube sections 132, each pair of such tube sections being suitably secured together by brackets 133 which may be welded thereto. The various sections of the distributing conveyor are detachably connected by couplings 134 and the lower tube 132 of each section is provided with a gate 136 which may be selectively opened by manipulation of a lever 137 secured thereto, the gate being normally spring urged to closed position. Below the selected gate a discharge conduit may be provided including a flexible hose 138 having funnel shaped feed chute 139 suspended by bowl 140 from the conveyor. The end section of the horizontal conveyor is provided by a housing 141 in which an idler sprocket 142 is suitably mounted to be driven by the flights of the cable conveyor so that if no gate 136 is opened, the material will be circulated through the distributing system until removal thereof at a desired point by opening a selected gate 136.

The swivel mounting of the hopper 111 provides for swinging movement of the conveyor 18 through a desired arc so that it may be readily readjusted to provide the desired location of the gates 136 for discharge of the material.

While I have shown and described certain preferred embodiments of the invention it is to be understood that the invention is capable of both variation and modification from the forms shown. 5 Therefore the scope of my invention should be limited only by the scope of the claims appended hereto. I, therefore, claim as my invention:

1. In a hoisting system, a circulating conveyor comprising a hopper, two conduits of tubing leading upwardly therefrom providing a hoisting conduit and a return conduit, an endless cable extending through said conduits having material conveying flights secured in spaced relation therewith, means for guiding and driving said cable to travel through said hopper and said tube, a discharge chute for receiving material from the discharge end of said hoisting conduit, and selectively operable means associated with said discharge chute for directing material therefrom to said return conduit.

2. In a hoisting system, a circulating conveyor comprising a hopper, two conduits of tubing leading upwardly therefrom providing a hoisting conduit and a return conduit, an endless conveyor traveling through said hopper and said conduits for carrying material therethrough, a discharge chute for receiving material from the discharge end of said hoisting conduit, and an auxiliary return conduit leading from said discharge chute to said first-named return conduit.

3. In a hoisting system, a circulating conveyor comprising a hopper, two conduits of tubing leading upwardly therefrom providing a hoisting conduit and a return conduit, an endless conveyor traveling through said hopper and said conduits for carrying material therethrough, a discharge chute for receiving material from the discharge end of said hoisting conduit, an auxiliary return conduit leading from said discharge chute to said first-named return conduit, and means for selectively opening and closing said auxiliary return conduit.

4. In a hoisting system, a circulating conveyor comprising a hopper and two conduits of tubing leading upwardly therefrom, together with an endless conveyor extending through said hopper and said conduits, said two conduits providing a hoisting conduit and a return conduit, a surge chamber in said hopper at the lower end of said hoisting conduit, a discharge chute associated with the discharge end of said hoisting conduit, and selectively operable means for causing discharge of material from said discharge chute to a point of disposal and for returning material from said chute to said return conduit for recirculation therein.

ALLEN L. STONE.
